UNITED STATES PATENT OFFICE

2,636,570

CRUDE OIL AND GAS SEPARATOR

Anthony J. Vallier, Los Angeles, Calif.

Application December 1, 1949, Serial No. 130,516

4 Claims. (Cl. 183—2.7)

1

This invention relates to the separation and washing of gases from crude oil.

An object of the invention is to provide simplified improvements in apparatus for the separation of gas from crude oil.

Another object of the invention is to provide improved apparatus of the character described whereby the separation of gas from crude oil may be accomplished in a substantially continuous operation.

More specific objects and advantages of the invention will appear and be brought out more fully in the following specification, reference being had to the accompanying drawings wherein:

Fig. 1 is a side elevation view of a gas washing unit embodying my invention.

Fig. 2 is an end elevation view of the same.

Fig. 3 is a sectional elevational view taken along the line 3—3 of Fig. 2.

Fig. 4 is a partial sectional elevational view taken along the line 4—4 of Fig. 3.

Fig. 5 is a partial view showing a portion of the apparatus partly in section, also seen in Figs. 1 and 2.

Fig. 6 is an enlarged sectional view taken along the line 6—6 of Fig. 3.

Fig. 7 is a partial perspective view as seen from the line 7—7 of Fig. 3.

Referring more particularly to the drawings, I show a main separation tank 10 supported on a suitable framework 11, and a gas collector tank 12 suitably mounted above tank 10 and having a passage connection 13 therewith which extends into and through the top of tank 10.

A crude oil inlet pipe 14 leads through a valve 15 into the upper interior portion of tank 10 by pipe 16 which has a closed end 17 and a plurality of discharge slot openings 18, as shown. A plurality of collector and deflector plates 20 are secured as by welding or otherwise to pipe 16 between slots 18, plates 20 being inclined, and each plate 20 has a parti-circular drip formation 21 adjacent but spaced from end wall 22 of tank 10. Plate formations 21 each have a parti-circular notch or cut-out portion 23 by which the separation of the liquid crude oil is facilitated.

A pipe 24 extends through an end wall 25 of tank 10, and has a pick-up inlet 26 within tank 10 and above the bottom 27 thereof and leads through a valve 28 to an oil outlet pipe 30. Tank 10 has an access opening 31 provided with a suitable closure 32, and a ball float 33 is secured to a lever 34 which has a bearing mounting 35 in closure 32, a suitable indicator 36 being operatively associated with lever 34.

2

Tank 12 is provided with a safety valve or plug 37 and a dome 38 to which is connected a gas discharge pipe 40 having a pressure indicator 41 which leads to a collector chamber 42. Chamber 42 is provided with a valved bleeder pipe 43. Chamber 42 has a gas discharge outlet 44 provided with a valve 45, and a by-pass pipe 46 leads from chamber 42 through a regulating valve 47 and connected to discharge outlet 44. A plurality of downwardly directed parti-circular deflectors and baffles 48 are positioned across the opening of passage connection 13.

The operation of the invention should be apparent from the foregoing description. The gas laden crude oil is introduced through pipe 16 into tank 10 and discharges therein through discharge openings 18, and the liquid oil accumulates at a level indicated at 49 which is shown by indicator 36. Tank 10 is provided with a sludge discharge opening 50 and discharge pipe 51 provided with a valve 52. The gas which is freed within tank 10 is conducted through passage 13 into tank 12 and thence through pipe 40 and collector chamber 42 to the outlet 44, either directly or through by-pass 46. As the gas and oil mixture passes deflector plates 20, a considerable amount of oil is separated and collected thereon due to the reduction in speed of flow, and most of the gas and oil separation occurs in this portion of tank 10. Whatever additional oil is carried with the gas through passage 13 is collected and separated by baffles 48, which oil is returned to the level 49.

Having described my invention what I claim is:

1. A gas washer as described, comprising in combination an elongated horizontal separating tank having a crude oil inlet, an oil outlet and a gas outlet, said inlet comprising a horizontal pipe extending into the tank a substantial distance and having a plurality of openings in the lower portion thereof, a plurality of inclined deflector plates; one below each of said openings and terminating adjacent a wall of the tank, the lower edges of said plates having flanged dispersion drip formations.

2. A gas washer as described, comprising in combination an elongated horizontal separating tank having a crude oil inlet, an oil outlet and a gas outlet, said inlet comprising a horizontal closed end pipe extending into the tank a substantial distance and having a plurality of openings in the lower portion thereof, a plurality of inclined deflector plates; one below each of said openings and terminating adjacent a wall of

the tank, the lower edges of said plates having flanged dispersion drip formations.

3. The combination according to claim 2 wherein the gas outlet is positioned in the top of the tank and displaced horizontally a substantial distance from the inlet.

4. The combination according to claim 2 wherein the outlet has a plurality of baffle plates.

ANTHONY J. VALLIER.
